FIG. 3

JACOB T. BRADLEY, INVENTOR

BY
McMorrow, Berman + Davidson
ATTORNEYS.

UNITED STATES PATENT OFFICE

2,488,166

WASTE HEAT APPARATUS

Jacob J. Bradley, Philadelphia, Pa.

Application May 24, 1946, Serial No. 671,993

4 Claims. (Cl. 122—7)

1

This invention relates to a heating apparatus, and more particularly, to such a device for heating of water.

A primary object of this invention is the provision of improved apparatus adapted to be utilized with a range or stove or the like, whereby the heat from the stove which otherwise would be wasted by passage through the flue is utilized to heat water in a storage tank associated with the apparatus of the instant invention.

A further object of the invention is the provision of such an apparatus which may be readily detached from the stove or the like and which contains an independent fire box, whereby the water contained in the tank thereof may be readily heated independently of the stove.

A further object of the invention is the provision of such an apparatus provided with water-circulation means, including upper and lower coils whereby thorough heating of the water in a relatively short time is assured.

Still another object of the invention is the provision of such an apparatus which is sturdy and durable in construction, reliable and efficient in operation, and relatively simple and inexpensive to manufacture and assemble.

Other objects reside in the combinations of elements, arrangements of parts, and features of construction, all as will be more fully pointed out hereinafter and shown in the accompanying drawings, wherein there is disclosed a preferred embodiment of this inventive concept.

In the drawings:

Figure 1 is a vertical sectional view taken substantially along the center line of one form of apparatus embodying features of the instant invention, showing the same in association with a range or stove, a fragment of the latter being shown.

Figure 2 is a sectional view taken substantially along the line 2—2 of Figure 1, as viewed in the direction indicated by the arrows; and

Figure 3 is a transverse cross-section taken substantially in the plane of the section line 3—3 of Figure 1.

Similar reference characters refer to similar parts throughout the several views of the drawings.

Referring now to the drawings, the device of the instant invention comprises a casing generally indicated at 10, including upper and lower rectangular chambers generally indicated at 12 and 13, respectively disposed one above and one below an intermediate frame ledge 11. The lower chamber 13 is provided interiorly with supporting

2

frame members 14 for the ledge 11 and includes four headers 15, 15', 16, and 16', all of the headers being connected by spaced pairs of pipes 17, with the exception of connections between the headers 16 and 16'. The space between the headers 16 and 16' is thus left clear, providing access to a fire box 19, such access being permitted by means of a door 20 pivotally secured, as on hinge members 21, to the outside wall of the casing or housing 10.

A grate 22 is provided in the base of the fire box 19 and suitably supported by transversely extending members 23 and the door 20 may be provided with suitable draft openings.

15 The lower chamber 13 is provided with an extending breeching 25 comprising walls 26 in the lower of which is provided an aperture 27 adapted to receive the flue 28 of a conventional stove or range 29.

20 It will thus be seen that heat may be supplied to the headers, as well as the pipes 17, water being circulated through the headers and pipes in a manner to be more fully described hereinafter, either by means of a fire in the fire box 19, or by 25 means of a fire in the range 29, the arrangement being such that the device may be readily moved from its association with the range, if desired.

The upper chamber 12 includes headers 31, 32, 33, and 34, the headers 31 and 32 being connected by spaced parallel pairs of pipes 35, and the headers 32 and 33 connected by similar spaced pairs of pipes 36, while further pipes 37 connect the headers 33 and 34. Headers 31 and 34 are otherwise unconnected.

Vertical walls 40 define the exterior of a water tank, generally indicated at 41 and having interior vertical walls 43 provided with a top plate 44 defining an interior recess in the bottom of the tank. The base 45 of the tank is supported on suitable supporting angle irons 46, or the like, carried by the frame ledge 11. The plate 44 is apertured to accommodate a flue 47, which extends through a suitable sealing boss 48 interiorly of the tank 41, and upwardly through the top 49 of the tank. The flue 47 is provided with a damper 50 provided with an exterior operating handle 51, and terminates in a cross-header 52 provided with a stack 53. A riser 54, also provided with a damper 55 having an exterior operating handle 56, communicates with the space 57 between the wall of the tank 40 and the exterior wall of the housing 10 at the open side of the upper coil to provide an alternate path around the 55 coil in the upper chamber for the escape of heat

and gases from the upper chamber 12. An exterior water gauge including parallel horizontal pipes 66 connected by a water glass 67 is also provided, the pipes 66 extending through suitable apertures in the side wall 40 of the tank and being provided with suitable sealing washers 68.

A fluid connection including a pipe 60 extends from the header 15 to the header 32, while a second fluid connection extends from an aperture 61 in the base of the tank 41 through a pipe 62 into the lower extremity of the header 16'. Similarly, as best shown in Figure 2, an inlet 63 is provided adjacent the top of the tank 41 into the header 34, while an outlet 64 extends from the header 31 to the exterior of the housing 10, whereby water may be drawn from the system.

From the foregoing, the operation of the device should be readily understood. Fire, either in the range 29 or the fire box 19 heats water in the pipes 17, as well as the headers in the lower chamber, the heated water tending to rise through the connection 60 into the upper header 32, from which it passes through the pipes 35 to header 31, through pipes 36 to header 33, and then from header 33 it passes through pipes 37 to header 34. The rising hot water may exit from the upper coil into the tank through the connection 63, while water enters the lower coil through the pipe 62 at the base of the header 16'. Thus, a relatively continual circulation of water through the system is provided, generated by the variations in temperature of the water in various portions of the apparatus, insuring an effective heating of all the water in the tank 41, which hot water may be suitably drawn off through the outlet 64, as desired. Replacement water may be admitted to the tank through a pipe 65 extending through the top of the tank or by other means as may be found convenient.

From the foregoing it will now be seen that there is herein provided an improved water heating apparatus which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. Heating apparatus comprising a casing including upper and lower rectangular chambers, a header in each of the four corners of each chamber, a water tank in the upper chamber, pipes connecting the headers in the lower chamber, additional pipes connecting the headers in the upper chamber, a connection between one of the lower headers and an upper header, a water inlet from the bottom of said tank to the bottom of one lower header, and a water outlet adjacent the top of one upper header.

2. Heating apparatus comprising a casing including upper and lower rectangular chambers, a header in each corner of each chamber, a water tank in the upper chamber having a recess in the bottom thereof, pipes connecting the headers in

the lower chamber, additional pipes connecting the headers in the upper chamber, a connection between the top of one of the lower headers and the bottom of the superimposed upper header, a water connection between the bottom of said tank and the bottom of a second lower header, a water outlet adjacent the top of an upper header, and a flue extending through said tank and into said tank recess.

3. Heating apparatus comprising a casing including an upper and a lower rectangular chamber, a header in each corner of each chamber, a water tank in said upper chamber having a recess in the bottom thereof, pipes connecting the headers in the lower chamber, additional pipes connecting the headers in the upper chamber, a connection between the top of one of the lower headers and the bottom of the superimposed upper header, a water connection between the bottom of said tank and the bottom of a lower header, a water outlet adjacent the top of an upper header, a flue extending through said tank into the bottom recess thereof, and a hollow breeching extending laterally from said lower chamber and having an aperture in the bottom thereof to receive the flue of a range.

4. A water heater comprising a rectangular casing including an upper and a lower water heating chamber, four vertical headers in each chamber arranged in rectangular relationship, substantially horizontal pipes connecting the headers in each chamber on three sides of the rectangular arrangement thereof and constituting separate upper and lower heating coils, a rectangular tank in said upper chamber within the confines of said upper heating coil, a water connection between the bottom of said upper coil and the top of said lower coil, a second water connection between the bottom of said tank and the bottom of said lower coil, a third water connection between the top of said upper coil and the top of said tank, and a water outlet connection leading from said upper coil.
